RAILWAY TRAFFIC CONTROLLING
APPARATUS

Earl M. Allen, Swissvale, Pa., assignor to The
Union Switch & Signal Company, Swissvale,
Pa., a corporation of Pennsylvania

Application January 22, 1935, Serial No. 2,845
Renewed January 2, 1937

28 Claims. (Cl. 246—134)

My invention relates in general to railway traffic controlling apparatus for governing traffic over a single track stretch of railway having one or more switches associated therewith for enabling the routing of traffic over divergent routes, and more particularly it relates to that class of apparatus whereby the movements of the switches and signals associated therewith are controlled from a remote point, such, for example, as a central office.

In systems where the movements of a railway switch and its associated signals are controlled from a remote point, it is customary to provide approach locking circuits. One feature of my invention has to do with the provision of means which exactly checks that approach and all route locking has been applied before a signal can be cleared.

I further provide means for picking up the approach locking relay of stick and non-stick signal circuits without requiring the leverman, centralized traffic or control operator, a the case may be, to release the signal control relay at the time the train occupies the approach locking release section.

Another feature of my invention has to do with the arrangement of certain of the circuits in a manner which provides stop signal protection against the false picking up of the stop signal repeater relay should its control wire become falsely energized by virtue of a positive ground, cross or similar failure.

A still further feature of my invention comprises the provision of means for insuring the integrity of the track circuit shunt between the home and distant signal after a train has passed the distant signal, by so arranging the circuits that any loss of shunt cannot modify the pick-up circuits of the approach or route locking relays to thus effect the release of the approach or route locking, except when a train passes the home signal and releases approach locking in the regular manner or through operation of a time element relay. Further features of my invention will appear from time to time a the specification progresses.

The apparatus of my invention is an improvement over that disclosed in the copending applications Serial No. 416,061, filed December 23, 1929, by Howard A. Thompson for Multiple control apparatus; Serial No. 695,294, filed October 26, 1933, by Allen and Thompson for Interlocking control apparatus; and Serial No. 14,868, filed April 5, 1935 by Allen and Thompson for Interlocking control apparatus.

I have illustrated my invention in three sheets of drawings comprising Figs. 1^a, 1^b and 1^c. These figures, when placed side by side with Fig. 1^a to the left of Fig. 1^b, Fig. 1^c to the right of Fig. 1^b, and with the corresponding track rails in alignment, form a diagrammatic view of the apparatus and circuits embodying my invention when applied to a stretch of track over which traffic normally moves from left to right, but over which traffic sometimes moves in the reverse direction. The track also has a number of associated railway switches via which traffic may be routed. The switches employed are designated by the numerals 1, 3 and 5 and may be operated by any standard type of switch machines, not shown, but which are well known and may be controlled in any desired known manner. In the present instance, the operation of the switch machines of switches 1, 3 and 5 is assumed to be by switch control relays under control of operator controlled relays to be referred to later.

By means of insulated joints 101 the track rails 102 and 103 are divided into track sections B1T, A1T, 1T, 3T, 5T, A5T, and B5T, respectively. Each track section is provided with a customary track circuit which includes a track battery and a track relay in a manner readily understood from the drawings. A two-position semi-automatic non-stick wayside signal R4A is employed in governing the movement of eastbound trains over the main track of the stretch-while the reference character D4 designates a three-position fully automatic distant signal for R4A. The signal R4B is of the two-position manual call-on type and is employed to permit trains to enter the stretch of track controlled by the signal R4A, while such track is occupied and also to direct eastbound traffic, over the alternative or secondary routes, namely over switch 3 or 5 reversed. The signal R4C, associated with the side-track of switch 1, is also of the manual type and permits eastbound trains to enter the main line track both for train movements over the main line and also for movements via switches 3 and 5 reversed.

The signal L4A governs westbound traffic movements over the main track and over a diverging route via switch 1 reversed and functions as a manual signal for movements exclusively over the main track and as a semi-automatic stick signal 50 when cleared for movements over the diverging route. The signals L4B and L4C are of the same type as R4C and govern the traffic movements to the main line from the switches 3 and 5 reversed, respectively. The signals employed may 55

be of any well known type, but as here shown, are color light signals of the searchlight type, such as disclosed in the United States Reissue Patent No. 14,940, granted to E. J. Blake.

5 In order to simplify the figures somewhat and to make them easier to understand, I have, in a number of instances, placed circuit controlling contacts and armatures in locations that are not adjacent to the relays that control them. In all 10 such instances these contacts or armatures are designated by the reference character of the relay to which they belong, and have an additional numerical designation. The contacts 20 of Fig. 1^a, for instance, having associated therewith the reference character 1ESR are controlled by relay 1ESR of Fig. 1^b and these contacts are shown in their normal or closed position.

In Fig. 1^a are shown circuit controllers 26, 27 and 28 which are operated by switch 1. Each controller occupies its upper position, indicated by the solid line, when the switch is set for the main track; while each controller occupies the down position, indicated by the dotted line, when switch 1 is set for traffic movements between the main track and the siding. The switch control relay 1W for switch 1 is a direct current polarized relay having polar armatures that remain in the position to which they have moved when last energized. This relay 1W, when energized with current of normal polarity, moves its polar armatures to a normal position that selects the operating circuit (not shown) for the switch machine (not shown) of switch 1 and this results in switch 1 being positioned for traffic on the main line. 35 With current of reverse polarity supplied to the relay 1W, then its polar armature is moved to a reverse position that selects the operating circuit for the switch machine that result in switch 1 being positioned for traffic between the main line and the siding. In the present drawings, the normal position of the polar armatures of relay 1W, and of all other polar relays, is left-hand, and the reverse position is the right-hand position, that is opposite from that shown.

45 The switch control relay 1W is controlled by remote controlled relays 1X and 1Y. With normal relay 1X selected by the operator and its armatures 48 and 49 raised, current is supplied to the relay 1W by a circuit extending from the positive terminal B of any suitable current source, not shown, but the opposite terminals of which are herein designated B and C, respectively, armature 46 and its back contact, the front contact and armature 48, contacts 20, 19 and 29 of 50 relays 1ESR, 1WSR, and 1TR, respectively, the winding of relay 1W, armature 49 and its front contact, and the back contact and armature 47 to the negative terminal C. The polarity of current thus supplied moves the polar armatures of 55 relay 1W to the left-hand side and thus brings about the normal positioning of the switch. With the operator selecting the reverse relay 1Y and with relay 1X released, it will be apparent that the flow of current to relay 1W is in the reverse direction to that formerly traced and, accordingly, the polar armatures will be reversed to the right-hand position with the result that the switch 1 is set for traffic between the siding and the main line.

60 The switch controlled relay 1KR is controlled jointly by the switch 1 and the relay 1W. With the switch set in the normal position, and relay 1W also in its normal position, the circuit of relay 1KR extends from the positive terminal B, controller 28, winding of relay 1KR, normal contact

and armature 104, through the controller 26 to the negative terminal C. With the switch 1 and relay 1W in their reverse position the circuit for relay 1KR extends from the positive terminal B through controller 27, the reverse contact and armature 104, winding of relay 1KR and the controller 28 to the negative terminal C. The switch control indication relay 1KR when energized controls associated normal or reverse switch position indication repeating relays 1NP and 1RP over neutral contacts 53 and the polar armature 54. It is to be understood that the circuits which ordinarily extend between the windings of the switch controlled relays 3KR and 5KR of switches 3 and 5 and the circuit controllers of these switches and relays associated therewith corresponding to 1X and 1Y, all of which are ordinarily provided, have been omitted from the drawings for the sake of simplicity. This equipment and associated circuits, however, is quite similar to that shown for controlling relays 1W and 1KR and will, therefore, be readily understood.

The direction of traffic over the stretch and its various branches is selected by directional control relays R4HS and L4HS, respectively, which may be directly controlled from a remote point by a leverman or by codes selectively transmitted over a centralized traffic control system in exactly the same manner as are the relays 1X and 1Y.

30 The various switches, signals and relays disclosed are shown in their normal positions, with the R4 signal repeating relay R4RGP, special function relays A1TPZ and 1TS, the approach locking relays 1ESR and 5WSR and the route locking relays 3ESR, 5ESR, and 1WSR picked up. The pick-up circuit for relay R4RGP extends from the positive terminal B through contacts 8, 9, 6, 7, 2 and 4 of the signal mechanisms R4CM, R4AM, R4BM of signals R4C, R4A, and R4B, respectively, through contacts of a distant relay D4RHP also picked up over an obvious circuit, contacts 60 of relay R4HS and the winding of relay R4RGP to the negative terminal C.

35 The relay 1ESR is being held energized over an obvious stick circuit after having been picked up over a circuit including the positive terminal B, contacts 67, over one of the three obvious possible multiple paths to the contacts 62 and through the winding of relay 1ESR to the negative terminal C.

40 The relay 5WSR is being held energized over a stick circuit extending from the positive terminal B, through contacts 106, 98, 107, 99, 103 and 100 of the mechanisms of L4CM, L4AM and L4BM of signals L4C, L4A and L4B, respectively, contacts 71 of relay L4HS, armature 55 of relay 5WSR and its front contact and the winding of relay 5WSR to the negative terminal C. This relay was initially picked up over a circuit similar to that traced, but including one of the four other obvious multiple paths extending between contacts 71 and the relay winding. The pick-up and stick circuits of each of the relays A1TPZ, 1TS, 3ESR, 5ESR and 1WSR are closed and are 45 so obvious as to make the tracing of these circuits unnecessary.

45 It is believed that an understanding of the invention can best be obtained by describing the various operations which occur during the usual traffic movements. It will first be assumed that the operator picks up control relay R4HS to clear signal R4A for an approaching train. This relay, on picking up, at its contacts 68, opens the circuit of relay R4RGP. The relay R4HS also at 50

armature 69 interrupts a point in an operating circuit common to the L4 signals and closes a point in a circuit common to the R4 signals. The relay R4RGP, upon restoring, at contacts 67 interrupts the circuit of the approach locking relay 1ESR. The relay 1ESR in turn releases and at contacts 113 interrupts the circuit of route locking relay 3ESR. This latter relay now also releases and at its contacts 33 interrupts the circuit of relay 5ESR. The relay 5ESR, on releasing, at contacts 52 closes the common portion of multiple circuits extending through the winding 80 of signal R4A and relay R4HSP respectively. The circuit extends from the positive terminal B at contacts 56 of relay 5ESR, through contacts 52 of relay 5ESR, the back contact and armature 73 of relay L4HS, neutral contacts 94 of relay 5KR, the normal contact and polar armature 93 of relay 3KR and its neutral contacts 911, the neutral contacts 119 of relay 1KR, and armature 69 of relay R4HS and its front contact where the circuit divides, one branch extending via contacts 114 of relay 1ESR, contacts 68 of relay R4RGP, the polar armature 86 and normal contact of relay 1KR, armature 66 and back contact of relay 4US, through contacts 74-79 of relays 5NP, 3NP, 1TR, 3TR, 5TR and A5TR, respectively, and through the winding 80 of signal R4A to the negative terminal C. The signal R4A accordingly changes from "stop" to "proceed", and in so doing, at contact 6 of its operating mechanism R4AM, opens a second point in the circuit of relay R4RGP, and closes an obvious circuit through the distant relay 4DR. The relay 4DR in lifting its armatures 43 and 44 reverses the direction of current flow through the winding 45 of signal D4 which accordingly moves to "clear", and at contacts 82 of its mechanism D4M opens the circuit of relay D4RHP.

40 The other branch of the circuit closed by contacts 52 of relay 5ESR extends via the front contact and armature 95 of relay A5TR, through the back contact and armature 65 of relay 4US and through the winding of slow operating and slow releasing relay R4HSP to the negative terminal C. After a slight delay relay R4HSP operates and at its contacts 63 places a shunt around the now open contacts 60 of relay R4HS. The relay R4RGP remains deenergized, however, since its circuit is now open at contacts 6 of the R4A signal mechanism R4AM as already explained, and also at the contacts on the D4RHP relay which is controlled from contacts 82 of mechanism D4M.

45 If there is stray operating potential on the conductor extending between the contacts of relay D4RHP and contacts 60 of relay R4HS, the relay R4RGP will be again picked up as soon as the contacts 63 of relay R4HSP close, and will accordingly, at contacts 68 again interrupt the circuit 50 of the cleared signal and such signal will immediately return to stop. On the other hand, it will be apparent that should a cross with the conductor leading to terminal C become applied to the conductor extending from the relay R4RGP 55 and shunt the normal current therefrom the relay R4RGP will deenergize, but none of the R signals will be cleared unless the directional relay R4HS has been picked up to clear one of such signals.

60 70 Aside from the foregoing protective features of the circuits I employ, before the signal R4A can be cleared; all track relays of the stretch must be energized, indicating the unoccupied condition of the stretch; the normal position switch repeating relays 3NP and 5NP must be energized, there-

5 by repeating the normal position of these switches; indication relays 1KR and 3KR must be energized and have their polar armatures in their normal position, thereby checking the position of the switches as well as that such position agrees with that of its switch control relay; relay 5KR must be energized to check that switch 5 is in a position in agreement with its control relay; the directional control relay L4HS must be deenergized, thereby checking against any attempt to clear the L4 signals; and finally route locking relay 5ESR must be deenergized. Now since the deenergization of relay 5ESR is dependent on the release of relay 3ESR, and since the release of relay 3ESR is dependent on the release of relay 1ESR, and further, since the release of 1ESR is assured by the release of relay R4RGP by relay R4HS, assurance is had that all of these relays will be deenergized at the time signal R4A is cleared. It will be observed from the 10 control circuit of switch control relay 1W that this relay cannot be operated to move the switch while contacts 20 of relay 1ESR are open. In like manner, the control relays 3W and 5W of switches 3 and 5 are disabled by contacts 201 and 202 of 15 their respective 3ESR and 5ESR route locking relays, when deenergized.

20 It will now be assumed that signal R4A has been cleared and that an eastbound train enters the approach section B1T. When this occurs 30 track relay B1TR restores and at its contacts 24 opens a point in the pick-up circuit for approach locking relay 1ESR. As the train enters approach section A1T the track relay A1TR restores and at its contacts 96 opens the pick-up and stick 35 circuits of relay A1TPZ. The pick-up circuit of this relay is now also open at contacts 116 of relay 1ESR. Relay A1TPZ therefore restores, and at contacts 22 opens a second point in the pick-up circuit of relay 1ESR. Ordinarily, the release of 40 relay A1TPZ is of no consequence, because, with the signal R4A at "proceed" the pick-up circuit of relay 1ESR is held open at contacts 67 of relay R4RGP.

45 If, however, the relay R4HS is released while there is a train in approach section A1T, the relay R4HS, at armature 69 opens the circuit of signal R4A. This signal accordingly returns to "stop" and at its contacts 6 reestablishes the circuit through relay R4RGP, relay D4RHP having closed 50 its contacts on entry of the train into section A1T. Under the foregoing circumstances, should a loss of shunt occur causing contacts 96 of relay A1TR to momentarily close while the train is in section A1T, relay A1TPZ serves to prevent the 55 possibility of the loss of the approach locking for the reason that contacts 22 of relay A1TPZ are open and cannot be closed until the train is actually in the detector section 1T, as the pick-up circuit of relay A1TPZ includes the now open 60 contacts 116 of the relay 1ESR.

65 When, however, the circuit of signal R4A is interrupted and relay R4RGP is again picked up, this relay, at contacts 67, closes a circuit for the usual time element relay 4TER, via armature 112 65 of relay 1ESR and its back contact. After the usual operating time of relay 4TER this relay at contacts 41 closes an obvious circuit through the relay 1ESR. If the train is still in the approach section, release of approach locking is effective 70 and switch 1 may be moved by operating relay 1W. Obviously, the operation of this relay is prevented by contacts 29 of track relay 1TR being open if the train has by this time entered the detector section 1T.

In case signal R4A is cleared for an approaching train and then returned to "stop" after such train enters section A1T and the train then backs out of the stretch the picking up of the approach locking relay 1ESR will also only occur through operation of the time element relay 4TER. This is true because relay A1TR on picking up cannot complete the pick-up circuit for relay A1TPZ because relay 1TR has not been deenergized to reclose the pick-up circuit of relay 1ESR. Since the L signal network includes contacts 115 of relay 1ESR, the foregoing timing arrangement prevents the operator from being able to, immediately after returning the R signal to "stop", clear one of the L signals before the train has had time to enter section 1T or back out of section A1T.

For the time being it will be assumed that signal R4A has been cleared, a train has entered section A1T, that accordingly relays A1TR and A1TPZ have become deenergized as already described, and that relay R4HSP remains picked up. When the train enters section 1T, track relay 1TR releases and at contacts 76 opens the circuit traced to the winding 80 of signal R4A. The signal R4A accordingly goes to "stop" and at contacts 6 reestablishes a circuit through relay R4RGP. This circuit is the same as that originally existing except that it now includes contacts 63 of relay R4HSP instead of contacts 60 of relay R4HS.

The relay R4RGP, upon picking up, at contacts 68 opens a second point in the operating circuit of signal R4A, and at contacts 67 closes a pick-up circuit for relay 1ESR including contacts 23 of relay 1TR and 62 of relay R4HSP. The relay 1ESR on picking up, at armature 112 prevents the operation of relay 4TER and establishes a stick circuit for itself independent of the track relay 1TR. The relay 1ESR also at contacts 116 reestablishes the circuit through relay A1TPZ and this latter relay accordingly again picks up. Finally, the relay 1ESR, at contacts 113, closes a point in the pick-up circuit of relay 3ESR, but this circuit is now held open by contacts 35 of track relay 1TR.

When the train enters section 3T relay 3TR releases, at contacts 77 opens another point in the circuit of signal R4A, and at contacts 34 opens a second point in the pick-up circuit of relay 3ESR. The relay 3TR also, at contacts 59, opens a point in the pick-up circuit of relay 1WSR, but without effect in view of the already established stick circuit in shunt of contacts 59.

When the train clears section 1T track relay 1TR again picks up, at contacts 76 closes a point in the circuit of signal R4A, closes a second point in the pick-up circuit of relay 1WSR at contacts 70, and at contacts 23 opens the pick-up circuit of relay 1ESR. The relay 1TR also, at contacts 29, again renders the switch control relay 1W operable to change the position of switch 1.

When the train enters section 5T the track relay 5TR restores, at contacts 78 opens a point 65 in the circuit of signal R4A, at contacts 58 opens another point in the pick-up circuit of relay 1WSR, and at contacts 36 opens a second point in the pick-up circuit of relay 5ESR. The relay A5TR also, at armature 95, opens the initial 70 circuit of relay R4HSP and closes a stick circuit for this relay including its contacts 64 and contacts 61 of relay R4HS.

When the train clears section 3T, the track relay 3TR again picks up, at contacts 77 closes 75 a point in the circuit of signal R4A, at contacts

59 recloses a point in the pick-up circuit of energized relay 1WSR, at contacts 91 opens a point in a pick-up circuit of relay 5WSR, and finally, at contacts 34, completes the pick-up circuit through relay 3ESR. The relay 3ESR on picking up, at contacts 31, reestablishes its stick circuit and at contacts 33 closes a point in the pick-up circuit of relay 5ESR. The relay 3ESR at contacts 201 renders the control relay 3W of switch 3 operable to change the position of switch 3. 10

When the train clears section 5T the relay 5TR again picks up, at contacts 78 recloses a point in the circuit of signal R4A, at contacts 89 opens a point in a pick-up circuit of energized relay 5WSR, at contacts 58 closes the pick-up current 15 of energized relay 1WSR, and at contacts 36 completes the pick-up circuit of relay 5ESR. The relay 5ESR on picking up, at contacts 51 closes one point in its stick circuit, and at contacts 52 interrupts the circuit originally closed to supply positive potential to signal R4A and relay R4HSP. With the track relay 5TR and route locking relay 5ESR picked up, the operating circuit for relay 5W is prepared at contacts 291 and 202, so that it may be operated to effect movement 25 of switch 5 in the same manner that such a circuit is prepared for control relay 1W of switch 1, or relay 3W of switch 3.

When the train clears section A5T its track relay A5TR again picks up and at its contacts 79 recloses a point in the circuit of signal R4A. The signal does not yet clear, however, as its circuit is still open at contacts 68 of relay R4RGP, 35 114 of relay 1ESR and 52 of relay 5ESR. The relay A5TR at armature 95 interrupts the stick circuit of relay R4HSP and again closes a point in the pick-up circuit of this relay. After a slight interval relay R4HSP restores and at contacts 64 opens a second point in its stick circuit. The relay R4HSP also, at contacts 63, interrupts the 40 circuit of relay R4RGP, which accordingly restores. The sequence of circuit changes which follow are identical to those previously described, as following the restoration of relay R4RGP by the picking up of relay R4HS. It will be obvious, 45 therefore, that the signal R4A will again automatically clear, and that the described cycle will be repeated as each following train or vehicle clears section A5T so long as the relay R4HS remains picked up. 50

If the relay R4HS is restored any time after a train enters the detector section 1T and before such train enters section A5TR the described operations will be modified somewhat. In such an instance when the train enters section A5T and relay A5TR releases, the pick-up circuit of relay R4HSP will be interrupted by armature 95 as previously described, but no stick circuit for this relay can be completed owing to contacts 61 of relay R4HS being open. Therefore, after a slight 60 interval, relay R4HSP releases and opens contacts 63. The opening of these contacts is ineffective at this time, however, owing to contacts 60 of relay R4HS now being closed. 55

When the train clears section A5T its track 65 relay A5TR again picks up and at its contacts 79 recloses a point in the circuit of signal R4A. The signal does not clear, however, as its circuit is now held open at contacts 68 of relay R4RGP, 70 114 of relay 1ESR, at the front contact and armature 69 of relay R4HS, and at the contacts 52 of relay 5ESR. Since relay R4HSP is already released the picking up of armature 95 is without effect at this time and the circuits are now in exactly the condition they were prior to the 75

5 picking up of relay R4HS. It will be seen, therefore, that with the arrangements herein provided, once the usual route has been set up for traffic in the normal direction over the stretch and the signal for such route cleared, the release of the directional control relay need not be effected until a different route is to be set up.

10 If the relay R4HS is picked up at a time that switch 3 is in its reverse position, the operations which follow will be modified, as it will be apparent that under these circumstances the normal switch indication relay 3NP will be deenergized and reverse indication relay 3RP will be picked up for reasons which will be obvious from 15 an inspection of the drawings. With relay 3RP picked up contacts 37 of this relay place a shunt about contacts 33 of relay 3ESR, and therefore, when 3ESR restores, following the picking up of relay R4HS, and the release of relays R4RGP 20 and 1ESR, it does not in this instance interrupt the circuit of relay 5ESR. It will be obvious, therefore, that relay 5ESR does not release as the route set up does not involve section 5T and therefore locking of the switch of this section is 25 unnecessary and may be undesirable.

The relay 3ESR now, however, extends positive potential from contacts 56 of relay 5WSR, through contacts 32 of relay 3ESR, the back contact and armature 72 of relay L4HS, the reverse 30 polar contact and armature 93 of relay 3KR, the neutral contacts 911 of this relay, neutral contacts 119 of relay 1KR, armature 69 of relay R4HS and its front contact, contacts 114 of relay 1ESR, 68 of relay R4RGP, polar armature 86 of 35 relay 1KR and its normal contact, contacts 82 of relay 3RP and through the winding 81 of signal R4B to the negative terminal C. The positive potential applied to this circuit also extends over the previously traced branch circuit including relay R4HSP.

40 The signal R4B now changes to "proceed" indication and at contacts 4 of its mechanism R4BM interrupts a second point in the circuit of relay R4RGP in the same manner as did the contacts 45 6 when signal R4A cleared. An instant later the slow acting relay R4HSP picks up, but operation of its contacts 63 is of no utility in the present instance as will be brought out subsequently. The signal R4B as herein employed simply advises an engineer that the train may enter the 50 stretch at slow speed. This signal is not placed under the control of the track relays and therefore maintains its proceed indication after the train enters the stretch.

55 When the train enters section 1T the track relay 1TR releases, at contacts 29 opens a second point in the circuit of switch control relay 1W, and at contacts 23 closes a point in the pick-up circuit of relay 1ESR. Since the operating circuit of signal R4B does not include contacts of track relay 1TR the circuit of this signal is not interrupted when the train enters the section. Therefore the contact mechanism R4BM of signal R4B does not establish a circuit through the 60 relay R4RGP when the section is entered. The relay 1ESR consequently does not pick up, and the control circuit for moving switch 1 is held open at contacts 29 of relay 1TR and also at contacts 20 of relay 1ESR.

70 When the train enters section 3T the track relay 3TR in releasing, at contacts 290 opens another point in the circuit of relay 3W, at contacts 34 opens another point in the pick-up circuit of relay 3ESR in addition to points in this circuit already open at contacts 35 of relay 1TR

and 113 of relay 1ESR. It will therefore be obvious that the control circuit for switch 3 cannot be closed while the train occupies section 3.

The operator can obtain control of switches 1 and 3 as soon as the train clears their respective sections 1T and 3T by releasing the relay R4HS. When relay R4HS is released, armature 69 opens the circuit previously extended to relay R4HSP and to the winding 81 of signal R4B. The signal now returns to "stop" and at contacts 4 of its mechanism R4BM reestablishes a circuit through relay R4RGP. The relay R4RGP at contacts 67 now completes the pick-up circuit of relay 1ESR. The relay 1ESR, on operating, at armature 112 prevents the operation of relay 4TER at this time. An instant later relay R4HSP releases and at its contacts 62 reopens the pick-up circuit of relay 1ESR. If, after clearing a signal such as R4B, relay R4HS is not released until after the train has cleared the detector section 1T, relay R4RGP, instead of at contacts 67 immediately completing the circuit of relay 1ESR via contacts 23 of relay 1TR, at contacts 67 first completes the circuit of time element relay 4TER for a sufficient time to enable it to operate. The relay 4TER then, at contacts 41 completes a circuit through relay 1ESR to pick it up.

When the train clears section 1T the track relay 1TR again picks up and at its contacts 29 again prepares the circuit of relay 1W to enable the operator to again move the switch.

When the train passes onto the switch 3 and clear of track section 3T, the track relay 3TR again picks up and at contacts 34 closes the pick-up circuit of relay 3ESR. The relay 3ESR in picking up, by closure of its contacts 201, again returns the control of switch 3 to the operator.

If the switch 5 is the one reversed, the operations are quite similar and it is believed a brief pointing out of the differences in the operation will suffice. With the switch 5 reversed, it will be obvious that its switch indication relay 5KR will have its armature moved to the right, its reverse position, and that its associated reverse indication relay 5RP will be picked up instead of its 5NP relay. The signal R4B is employed for either of the foregoing routes. With switch 5 reversed and switch 3 in its normal position, the contacts 37 of relay 3RP are open and the 5ESR relay is released to lock switch 5 in the same manner as when the R4A signal is cleared.

Likewise, the positive potential employed in energizing winding 81 of signal R4B and relay R4HSP passes over substantially the same path as when signal R4A was cleared, the only difference being that, with contacts 74 of relay 5NP open, current cannot flow to the winding 83 of signal R4A, but now flows via contacts 92 of relay 5RP and through the winding 81 of R4B to the negative terminal C. When the switch 5 is in its reverse position and signal R4B has been set at proceed, a train entering the stretch and passing on into section 3T clear of section 1T brings about operations identical to those occurring when switch 3 was reversed.

When the train enters section 5T the associated track relay 5TR releases and at contacts 291, corresponding to contacts 29 of relay 1TR, opens a second point in the control circuit of the switch 5, this circuit being already open at contacts 202 of relay 5ESR, corresponding to contacts 20 of relay 1ESR. The train in clearing section 3T effects circuit changes identical to those occurring when section 3T is cleared by a train leaving the section via switch 3. When the train has cleared 75

section 5T, the track relay 5TR at contacts 291 again closes one of the open points in the control circuit of switch 5, but since relay 5ESR has not yet been picked up, the switch remains locked from control by the operator. Control of switches 1, 3 and 5 can only be regained by releasing relay R4HS which will, in releasing, bring about the interruption of the circuit to signal R4B and effect the picking up of approach and route locking relays 1ESR and 3ESR in the manner previously described. Relay 3ESR on picking up at contacts 33 closes the pick-up circuit through relay 5ESR. With these relays all energized, control of the respective switches is returned to the operator.

It will be seen from the foregoing that if relay R4HS is restored while the train is in section 1T, the circuit to winding 81 of signal R4B and to the relay R4HSP will be interrupted at the front contact and armature 69 of relay R4HS and the energization of relay 1ESR will be brought about in the same manner as when relay R4HS is released with the train 1T and clear of section 3T, or 5T, as the case may be.

Under these circumstances, contacts 29 of relay 1TR prevent completion of the control circuit of switch 1, while contacts 35 of relay 1TR prevent the picking up of relay 3ESR. However, as soon as the train clears section 1T, the control circuit for switch 1 is available. Likewise, when the train clears section 3T, the pick-up circuit for relay 3ESR is closed at contacts 34 of relay 3TR. The relay 3ESR in picking up at contacts 201 restores control of the switch 3 to the operator. Whether the section 3T is cleared by the train entering a siding via switch 3 or by passing on into section 5T is obviously immaterial. If the train has been routed via switch 5 it will be obvious that contact 202 of relay 5ESR and contacts 291 of relay 5TR prevent the operator from obtaining control of switch 5 until the train has cleared section 5T.

There may be times during which there is already a train in the stretch which has entered under clearance of signal R4A, and that the operator desires to give a following train permission to also enter the stretch. Under these circumstances he may do so by setting the signal R4B to "proceed." This can be accomplished under these circumstances only by first releasing relay R4HS, picking up call-on signal control relay 4US and by then again picking up the relay R4HS.

The relay R4HS, on releasing, at armature 69 interrupts the circuit of relay R4HSP. Relay R4HSP, on releasing, at contacts 63 now interrupts the circuit of relay R4RGP, but R4RGP stays up because contacts 60 of relay R4HS are now closed. Now, when relay 4US is picked up, armature 65 excludes armature 95 of track relay A5TR from the operating circuit of relay R4HSP, and armature 66 at its back contact opens a further point in the circuit of signal R4A and at its front contact closes a point in the circuit of signal R4B. Now when the relay R4HS is again picked up, armature 69 completes circuits to relay R4HSP and to the winding 81 of signal R4B, respectively. As hereinbefore explained, signal R4B interrupts a second point in the circuit of relay R4RGP before relay R4HSP closes contacts 63 and therefore the relay R4RGP, and the approach and route locking relays 1ESR, 3ESR and 5ESR will deenergize and remain deenergized until the call-on signal resumes its "stop" indication. As soon as a train enters the stretch the operator ordinarily restores relay 4US. When this takes

place the relay 4US at armature 65 again places the picked up relay R4HSP under the joint control of track relay A5TR and R4HS. The relay 4US, at its armature 66 opens the circuit of winding 81 of signal R4B so that it will resume its "stop" indication, and again closes a point in the circuit of winding 80 of signal R4A. Signal R4B, in returning to its "stop" position, at contacts 4 again completes the circuit of relay R4RGP.

It will now be recognized that the circuits and relays of the stretch are in the same condition as described when a train was proceeding through the stretch after entering it under clearance of signal R4A and therefore when both trains have cleared the stretch signal R4A will again clear if relay R4HS has not in the meantime been again restored, as under these conditions both the stick and pick-up circuits of relay R4HSP will be open, and relay R4HSP will accordingly release to effect the release of relay R4RGP and the consequent release of relays 1ESR, 3ESR and 5ESR as is necessary to the completion of the circuit of signal R4A.

It will be noted that the following train need not necessarily follow the first train through the stretch, for, as previously explained, when the first train clears section 3T the 3ESR relay is picked up and the position of switch 3 may be reversed thereafter and any time prior to the entry of the following train into section 1T.

It will now be assumed that the operator picks up relay R4HS for the purpose of clearing signal R4C to permit a train to enter the stretch via switch 1 reversed. It will be obvious that, before this can be done, switch 1 must be operated to its reverse position and that such reversal must be checked by the movement of the polar armature 86 of the associated switch indication relay 1KR to its reverse position. One or the other of the switches 3 or 5 may, of course, also be reversed at this time if the train is to follow one of the secondary routes. With switch 1 in its reverse position, relay R4HS, on picking up, effects circuit changes as hereinbefore described in connection with the clearance of signals R4A and R4B except that since armature 86 of relay 1KR is now in its reverse position the signal circuit completed includes conductor 87 and the winding 88 of signal R4C. The signal R4C, in moving to "proceed" position, at contacts 9 interrupts a second point in the circuit of relay R4RGP in the same manner as did signal R4B on clearing.

It will be observed that the circuit of the R4C signal winding 88 is quite similar to that of winding 81 of signal R4B in that neither of these circuits include contacts of any of the track relays of the stretch. It follows, therefore, that once the switches have been set for the route desired and the signal R4C cleared, such signal will remain cleared until its circuit is interrupted by the release of relay R4HS. The picking up of the relay 1ESR following the release of relay R4HS to return signal R4C to "stop" is accomplished in the same manner as when the relay R4HS is released to return signal R4B to "stop".

Attention is now directed to the control of train movements over the stretch in the opposite or westbound direction, against the normal direction of traffic. For such movements dwarf signals L4A, L4B and L4C, permitting westward movement of traffic, only under caution signal indication, is provided for. In order to illustrate that the present invention can be employed in conjunction with semi-automatic stick signals,

as well as in circuit arrangements employing semi-automatic non-stick signals, such as R4A, the operating winding 84 of signal L4A is included in a circuit controlled by track relays 5TR, 3TR and 5TR when switch 1 is in its reverse position, but shunted by contacts of the normal indication repeating relay 1NP when the switch 1 is in its normal position, thereby changing the character of signal L4A from the manual 10 to the semi-automatic stick type when such signal is cleared after the reversal of switch 1. The windings 82 and 85, respectively, of signals L4B and L4C are included in operating circuits generally similar to those of signals R4B and 15 R4C in that they do not include contacts of the track relays. The signals L4B and L4C, therefore, are manually controlled at all times.

It will now be assumed that, with switch 1 in its normal position, the operator picks up the 20 control relay L4HS to clear signal L4A to permit a westbound train to enter the stretch. Relay L4HS, in picking up, at contacts 71 opens the stick and pick-up circuits of the approach locking relay 5WSR; at armatures 72 and 73 opens points in 25 the operating circuits of all of the R4 signals, thereby insuring that such opposing signals are at stop; and at the front contacts of these armatures closes points in the operating circuits of all of the L4 signals. The relay L4HS also 30 at contacts 109 opens the pick-up circuit of relay 1TS, but without effect at this time because of the previously established stick circuit through this relay.

The relay 5WSR in releasing, at contacts 56 35 opens a further point in the circuits of the R4 signals; at contacts 191 opens a point in the circuit of relay 5W, thereby locking switch 5 against operation; and at contacts 57 interrupts the stick and pick-up circuits of route locking 40 relay 1WSR. The relay 1WSR, on releasing, at contacts 19 opens the control circuit of switch 1 and opens a pair of contacts 199 included in the control circuit of switch 3, thereby effectively locking these switches against operation. The 45 relay 1WSR also, at contacts 17 now connects the positive terminal B to the winding 84 of signal L4A via contacts 115 of relay 1ESER, the back contact and armature 69 of relay R4HS, the neutral contacts 119 and 911 of relays 1KR and 3KR, respectively, the polar armature 93 of relay 3KR and its normal contact, the neutral contacts 94 of relay 5KR, armature 73 of relay L4HS and its front contact, the polar armature 83 of relay 5KR and its normal contact, contacts 15 of stick 50 relay 1TS, and the winding 84 of signal L4A to the negative terminal C. The signal L4A accordingly moves to its "proceed" indicating position and in so doing opens its contacts 107, thereby opening a second point in the pick-up and stick 55 circuits of relay 5WSR. When the westbound train enters section 5T the relay 5TR, in releasing, at contacts 291 opens a second point in the control circuit of switch 5, and at contacts 89 closes a point in a pick-up circuit of relay 5WSR. The 60 operator may now release relay L4HS to return signal L4A to "stop" by opening its circuit at armature 73 and at contacts 71 reclose the initially opened point in the pick-up circuit of relay 5WSR. The signal L4A in returning 65 to "stop" position, at contacts 107 again completes the obvious pick-up circuit for relay 5WSR including the contacts 89 of track relay 5TR. The relay 5WSR thereupon picks up and at its 70 armature 55 opens the circuit extending to time element relay 4TER before that relay can oper-

ate, and at its front contact reestablishes its stick circuit. The relay 5WSR also, at contacts 57 closes a point in the pick-up and stick circuits of relay 1WSR, and at contacts 191 closes a point in the control circuit of switch 5. The 5 previously mentioned contacts 291 of track relay 5TR, however, now prevent the control circuit for switch 5 being closed while the train remains in section 5T.

The signal L4A is at this time employed in 10 the same manner as are signals R4B and R4C. It will, therefore, be apparent from the foregoing description that, should the operator delay releasing the relay L4HS to return signal L4A to "stop", until after the train has cleared section 15 5T, the picking up of relay 5WSR will be brought about only through the medium of relay 4TER.

When the train enters section 3T the track relay 3TR restores and at contacts 59 opens another point in the pick-up circuit of relay 1WSR, and at contacts 290 also opens another point in the circuit of switch control relay 3W of switch 3.

When the train clears section 5T the track relay 5TR again picks up and by closing contacts 25 291 returns the control of switch 5 to the operator. The relay 5TR also, at contacts 89 again opens the pick-up circuit of relay 5WSR. The relay 5TR also, at contacts 58 recloses a point in the pick-up circuit of relay 1WSR, but since contacts 59 of relay 3TR are now open this circuit is not yet completed.

When the train enters section 1T the relay 1TR releases and at contacts 29 opens another point in the circuit of the switch control relay 1W thereby preventing movement of switch 1 while the train is in the section even with relay 1WSR picked up.

When the train clears section 3T relay 3TR again picks up to again close contacts 290 in the 40 control circuit of switch 3. Now, as soon as the train clears section 1T, by passing on into section A1T or by movement over switch 1, should that switch have been reversed prior to the entry of the train into the stretch, relay 1TR at contacts 45 70 again completes the pick-up circuit of relay 1WSR. Relay 1WSR on picking up, recloses its stick circuit at contacts 18 and at contacts 17 again disconnects the positive terminal B from the common portion of the operating circuits of 50 the L signals.

In the foregoing description it was assumed that the operator released the relay L4HS after the train entered section 5T to put the signal L4A to "stop." Since, with switch 1 in its normal position, relay 1NP at contacts 14 renders the operation of the track relay contacts 11, 12 and 13 ineffective, it will be apparent that if the operator does not release relay L4HS the signal L4A will continue to indicate proceed.

If, however, the switch 1 is reversed before the operator picks up relay L4HS to clear signal L4A, contacts 14 of relay 1NP will be open and contacts 141 of relay 1RP will be closed. Under these circumstances, when the train enters section 5T the circuit of relay 1TS is interrupted by the opening of contacts 13 of the track relay 5TR, and subsequently by contacts 12 of relay 3TR and 11 of relay 1TR. The relay 1TS accordingly releases and at contacts 143 completes 70 a shunt about contacts 89 of track relay 5TR, thereby enabling the operator to pick up relay 5WSR, and again obtain control of switch 5, without the delay which would otherwise be introduced by timing relay 4TER, should the oper- 75

ator delay the release of relay L4HS until after contacts 89 have opened. The relay 1TS at contacts 15 opens the circuit of winding 84 of signal L4A. The signal L4A accordingly automatically goes to its "stop" position. Under these circumstances before the signal L4A can be cleared for the same route, the track relays 5TR, 3TR and 1TR must have again picked up and the relay L4HS again released to, at contacts 109, 11, 12 and 13, reestablish the pick-up circuit of relay 1TS. The relay 1TS in picking up at contacts 144 reestablishes its stick circuit, at contacts 143 opens the shunt from around contacts 89 of track relay 5TR, and at its contacts 15 again closes a point in the circuit of winding 84 of signal L4A. To again clear signal L4A for a second train movement over the established route the operator again picks up relay L4HS whereupon the foregoing cycle of operations will be repeated.

It will now be assumed that the operator reverses the switch 5 as soon as the first westbound train entering the stretch has cleared section 5T and then again picks up relay L4HS to clear signal L4C to permit a train to enter the stretch over switch 5. With switch 5 reversed it will be apparent that its associated indication relay 5KR will have moved its polar armatures to their reverse position, that the associated normal indication repeating relay 5NP will be released, and that the reverse indication repeating relay 5RP will be picked up. The relay 5KR at its polar armature 83 and at its normal contact opens points in the circuit of winding 84 of signal L4A and at its reverse contact closes the circuit of winding 85 of signal L4C to clear such signal. It will be observed that, with switch 5 reversed, contacts 142 of relay 5NP will be open and therefore contacts 89 of track relay 5TR are not shunted. The manner of picking up relay 5WSR following the release of relay L4HS accordingly depends on the occupied or non-occupied condition of section 5T, in the same manner as when relay L4HS is released following the clearance of signal L4A with switch 1 at normal.

The usual approach or stick locking protection for westbound trains entering the stretch under clearance of signals L4A and L4C is provided. Since the operations are the same irrespective of which of the signals L4A or L4C is "cleared" and returned to "stop" a description of the operation only of one of the two instances will be necessary. It will be assumed, as an example, that the operator clears signal L4A and then returns it to "stop" in the face of an approaching train by first picking up and then releasing relay L4HS. The relay L4HS, in releasing now, at contacts 11 extends positive potential from terminal B and through contacts of the L signals, all in "stop" position, to the time element relay 4TER via armature 55 of relay 5WSR and its back contact and contacts 111 of relay 1ESR. If the train enters section 5T before the time element relay has had time to close its contacts 42 the relay 5TR will, at its contacts 89, complete the pick-up circuit of relay 5WSR, but the operator will now be prevented from operating the switch by the opening of contacts 291 of track relay 5TR.

If, on the other hand, the relay 4TER closes its contacts 42 before the train enters section 5T, relay 5WSR will pick up, and since the contacts 291 of relay 5TR included in the control circuit of switch 5 are still closed, will enable the operator to change the position of the switch.

In case one of the L signals is cleared for an

approaching train and is then immediately returned to "stop", the functioning of the time element relay 4TER in delaying the pick-up of relay 5WSR also prevents the operator from immediately clearing any R signal, as the common portion of the R signal network is held open by contacts 56 of relay 5WSR until such relay picks up.

It will now be assumed that the switch 3 has been reversed and that the operator picks up relay L4HS to clear signal L4B to enable a westbound train to enter the stretch at this point. As will be clear from the preceding description, with switch 3 reversed, its indication relay 3KR will have its polar armatures in engagement with their reverse contacts, the reverse indication relay 3NP is released, and relay 3RP is picked up. The relay 3KR therefore, at its polar armature 93, in moving to its reverse position, opens a common point in the circuits of windings 84 and 85 of signals L4A and L4C, respectively, and closes a point in the circuit of winding 82 of signal L4B. The relay 3NP on releasing, at contacts 90 removes the relay 5WSR from control by track relay 5TR, while the relay 3RP in picking up places relay 5WSR under control of contacts 91 of track relay 3TR.

The relay L4HS, on picking up now, at contacts 12 closes another point in the circuit of winding 82 of signal L4B, and at contacts 11 interrupts the stick circuit of relay 5WSR. The relay L4HS also at armature 73 closes a point in the common portion of the operating circuits of signals L4A and L4C, but without effect as these circuits remain open at armature 93 of relay 3KR, now in its reverse position. Relay 5WSR, in releasing, opens the control circuit of switch 5 and the circuit of relay 1WSR in the manner hereinbefore described. The relay 1WSR, in releasing, opens the control circuits of switches 1 and 3 as hereinbefore also fully explained, and at its contacts 17 now completes a circuit through winding 82 of signal L4B. This circuit will be obvious in the light of the preceding descriptions. The signal L4B in changing to "clear" at contacts 108 opens a second point in the pick-up circuit of relay 5WSR.

When the train enters section 3T, the track relay 3TR releases and at contacts 91 prepares a pick-up circuit for relay 5WSR, and as previously explained, opens a second point in the control circuit of switch 3. The operator may now release relay L4HS to return the signal L4B to "stop" by interrupting its circuit at contacts 72. The signal L4B in returning to "stop" again closes its contacts 108 thereby completing the prepared pick-up circuit for relay 5WSR directly, or through the medium of relay 4TER if the train has cleared section 3T. The picking up of this relay returns the control of switch 5 to the operator, but the open contacts 59 of track relay 3TR prevents the closure of contacts 57 of relay 5WSR from completing the circuit of relay 1WSR while the train remains in section 3. Since, as hereinbefore explained, the relay 1WSR has contacts 19 and 199 included in the 1 and 3 switch control circuits, neither of these switches can yet be moved by the operator. Furthermore, it will be observed that the pick-up circuit of relay 1WSR includes contacts 70 of track relay 1TR. It will, therefore, be apparent that before the relay 1WSR can pick up and restore control of switches 1 and 3 to the operator that both track sections 3T and 1T must be unoccupied. The usual route locking protection against movement

of switch 3, after signal L4B has been cleared and returned to "stop" in the face of an approaching train, is provided. Under such circumstances the relay L4HS, in restoring, at contacts 71 extends positive potential from terminal B and through contacts of the L signals, all in "stop" position, to the time element relay 4TER, via armature 55 of relay 5WSR and its back contact, contacts 111 of relay 1ESR to the winding 10 of time element relay 4TER and to the negative terminal C.

If the train enters section 3T before the time element relay has had time to close its contacts 42 the relay 3TR will, at contacts 91, complete 15 the pick-up circuit of relay 5WSR, and at contacts 59 open a point in the pick-up circuit of relay 1WSR. Therefore, on the subsequent picking up of relay 5WSR the closure of contacts 57 thereof will be ineffective to pick up relay 1WSR. 20 Accordingly, the operator is under these circumstances prevented from operating switch 3 by the open contacts 199 of relay 1WSR.

If, on the other hand, the relay 4TER closes its contacts 42 before the train enters section 25 3T, relay 1WSR will pick up consequent to the closure of contacts 57 of relay 5WSR. Since at this time contacts 298 of track relay 3TR are still closed, the operator is enabled to change the position of the switch.

30 From the foregoing, it will be seen that I have succeeded in the development of circuits, applicable to a combination of manual, semi-automatic stick, as well as semi-automatic non-stick, signals and that: (1) these circuits exactly check 35 that approach and route locking are effective before a signal can be cleared; (2) that the operator need not restore the control relay while the train is in the detector section; (3) that these circuits further, to a certain extent, check themselves should improper operation occur due to the presence of stray current; (4) and that they further include arrangements for effectively guarding against the improper release of approach and route locking consequent to a temporary loss of shunt in an approach section.

Having described my invention, what I consider to be new and desire to cover by Letters Patent will be further brought out in the claims hereunto appended.

50 1. In a signaling system, a signal displaying one indication when deenergized and another indication when energized, a relay energized over a circuit including contacts of said signal closed when the signal is deenergized, contacts on said 55 relay normally holding the circuit for energizing said signal open, a second relay having a pick-up circuit in multiple with the energizing circuit of said signal, but excluding contacts of said first relay, a third relay having contacts included in the circuit of said first relay and being 60 operable to release said first relay to complete circuits through said signal and said second relay respectively, the contacts on said signal opening a second point in the circuit of said first relay when the signal is cleared, and contacts 65 closed by said second relay in shunt of those opened by said third relay effective to again immediately pick up said first relay in case the opening of the contacts of said signal has failed 70 to remove operating potential from the circuit for said first relay.

2. In a traffic control system, a stretch of track, a signal for governing traffic entering such stretch, an approach locking relay for the stretch, 75 a signal control relay, a second relay normally

energized over a circuit including contacts of said signal control relay whereby operation of said signal control relay to clear said signal effects the release of said normally energized relay, contacts opened by the release of said second relay 5 to effect the release of said approach locking relay and the closing of a point in a circuit employed to clear said signal, a third relay, other contacts closed by operation of said control relay completing circuits through said signal to clear 10 it and through said third relay, contacts on said signal operated consequent to its clearance to open a second point in the operating circuit of said normally energized relay, and contacts on said third relay subsequently closed to place a 15 shunt about the contacts in the circuit of the normally energized relay opened by the picking up of said signal control relay whereby if a stray operating potential is encountered by any portion of the circuit extending between the open 20 contacts of the cleared signal and the contacts of said third relay the normally energized relay will again pick up and interrupt the circuit of said signal.

3. In a railway signaling system, a stretch of 25 railway track divided into a plurality of sections each equipped with a track relay, a railway switch adjoining one section of the track, an approach locking relay for said switch; a circuit for controlling the movement of said switch including 30 contacts of one of said track relays and of said approach locking relay, respectively; a signal for governing traffic entering the switch equipped section of said stretch, a manually controlled relay having means under its control for releasing 35 said approach locking relay, a circuit for clearing said signal completed by the release of said approach locking relay and including contacts subsequently opened by said manually controlled relay to permit the return of said signal to stop 40 prior to the entry of a train into the switch equipped section, and means delaying the picking up of the approach locking relay for a definite fixed period of time after said manually controlled relay has been released if the track relay 45 of the section to the rear of said signal has been released by a train therein even should such relay again pick up due to a subsequent loss of track shunt while the train is in such section.

4. In combination with a stretch of track divided into a plurality of insulated track sections each equipped with a track relay and wherein such stretch employs an approach locking relay for preventing the movement of a switch after an operation is performed to clear a signal governing traffic into the section of the stretch in which the switch is located until such protection is afforded by the release of the track relay upon actual entrance of a train into such section of the stretch, a second relay having a pick-up circuit opened by the release of the approach locking relay; a stick circuit for said second relay opened by the track relay of the section preceding the one with which a switch is associated, when a train enters such section; and contacts included in the pick-up circuit of the approach locking relay opened by the restoration of said second relay to prevent the picking up of the approach locking relay prematurely in case the track relay of such approach section again picks 70 up while the train is in such section.

5. In a traffic control system, a stretch of track including an adjoining track switch and being divided up into a plurality of sections including a detector section in which such switch 75

- is included and an adjoining approach section, an approach locking relay included in a normally closed circuit and having contacts normally closed to enable the movement of said switch, a 5 signal at the junction of said track sections for governing the movement of trains entering said approach section in a direction toward said detector section, means for opening the circuit of said approach locking relay and for clearing 10 said signal in the order named; a second relay having pick-up and stick circuits which are normally closed and the pick-up circuit of which is opened by the release of said approach locking relay and also having normally closed contacts 15 included in the pick-up circuit of said approach locking relay; and means controlled by a train entering said approach section for breaking the stick circuit of said second relay to thereby insure that said approach locking relay cannot thereafter pick up until the train has cleared said 20 approach section.
6. In combination, a section of railway track containing a switch, an approach locking relay, means for preventing operation of said switch unless said relay is energized, an auxiliary relay having a pick-up circuit including front contacts of said approach locking relay, a second section of track, a track circuit for said second section including a track relay connected across rails 25 thereof, a stick circuit for said auxiliary relay including front contacts of the track relay of said second section, and a pick-up circuit for said approach locking relay including front contacts of said auxiliary relay.
- 30 7. In combination with a stretch of track divided into a plurality of electrically insulated sections and also having associated switches over which trains may be routed over divergent paths, a signal at the entrance of the stretch for governing traffic therethrough, a first relay operable to clear said signal, a second relay normally energized over a circuit including contacts of said signal and of said first relay respectively, an approach locking relay for one of said sections, 35 position indication relays for the respective switches in the stretch, track relays for the respective sections of the stretch, a third relay, an energizing circuit for said third relay including a branch circuit for clearing said signal, said branch circuit including contacts of said track and approach locking relays, said first and second relays, as well as certain of said indication 40 relays to enable clearance of said signal only when said switches are in a particular position, and when said sections are all unoccupied, the track relay of the first section in advance of the 45 signal serving to insure the return of said signal to stop when the train enters the stretch, contacts on said third relay enabling the reenergization of said second relay in response to the return of said signal to stop, and means including said third relay for again clearing said signal as soon as the train leaves the stretch in certain 50 instances.
- 55 8. In a railway signaling system for a stretch of track, associated switches adjoining the main track of the stretch via which a train entering the stretch may be routed, signals at the entrance to the stretch for directing traffic over the various routes, remotely controlled means operated to effect the clearance of one of said signals to permit the passage of a train through the stretch over a selected route, a normally energized approach locking relay deenergized consequent to the actuation of said means to lock the 60

set route until the train has entered the stretch, other means for thereafter locking the route while the train remains in the stretch, means operated consequent to the entry of the train into the stretch to effect the restoration of the 5 cleared signal to stop, and means for also automatically effecting the deenergization of said approach locking relay to enable the automatic clearance of such signal for the set route as the train passes out of the stretch providing the remotely controlled means is still in its operated condition.

9. In combination with a stretch of track divided into a plurality of insulated track sections each provided with a track relay and certain sections of which have railway track switches associated therewith, a group of signals at one end of the stretch; operator controlled means for clearing one of said signals, the signal cleared being dependent on the position of a given one 20 of said switches at the time such means is operated; means controlled by the track relay of the first section of the stretch as it becomes occupied to enable a given cleared signal to return to stop only if a given switch in the exit section of 25 the stretch occupies a position other than a given position, and means controlled by the track relays of the subsequent sections after said first section of the stretch for positively preventing the clearance of such signal while any of such 30 sections are occupied.

10. In a traffic control system applied to a stretch of track having associated switches via which traffic may pass over different routes and over which traffic normally moves in one direction only, a signal at the exit end of said stretch for governing the movement of traffic against the normal direction, means for manually controlling said signal for traffic movement over one route of the stretch and for then manually returning said signal to stop, means for causing said signal to function as a semi-automatic stick signal when the same is cleared for a traffic movement over an alternative route over the stretch, another signal at the entrance to the stretch for governing traffic over the stretch in the normal direction, means operated to clear said latter signal, means operated in the course of the clearance of said latter signal for causing it to automatically return to clear indicating position after the train has passed through the stretch, and means for causing said signal to remain in its stop indicating position after the train has passed through the stretch in case the means operated to clear it has been restored prior to the exit of 50 the train from the stretch.

11. In a signaling system, a normally deenergized signal, a signal repeating relay normally energized when said signal is in its normal position, a signal control relay operable at will and having normally closed contacts included in the circuit of said signal repeating relay whereby operation of said control relay effects the release of said signal repeating relay, a slow to operate relay having normally open contacts connected in multiple with the normally closed contacts of said signal control relay for preparing a pick-up circuit for said repeating relay which is independent of said control relay, circuits for energizing said signal and for picking up said slow to operate relay closed by means jointly controlled by said control relay in operating and by said repeating relay in releasing, means actuated by said signal when energized to open a second point in the circuit of said repeating relay before said slow 70 75

- to operate relay closes its contacts to prevent the immediate picking up of said signal repeating relay, and means for subsequently temporarily interrupting the circuit of said signal to deenergize it to close the new circuit prepared for said repeating relay to pick it up and thereby hold the circuit of said signal open after said temporary means has ceased to function.
12. In a signaling system, a normally deenergized signal, a signal repeating relay normally energized when said signal is in its normal position, a signal control relay operable at will and having normally closed contacts included in the circuit of said signal repeating relay whereby operation of said control relay effects the release of said signal repeating relay, a slow to operate relay having normally open contacts connected in multiple with the normally closed contacts of said signal control relay for preparing a pick-up circuit for said repeating relay which is independent of said control relay, circuits for energizing said signal and for picking up said slow to operate relay closed by means jointly controlled by said control relay in operating and by said repeating relay in releasing, means actuated by said signal when energized to open a second point in the circuit of said repeating relay before said slow to operate relay closes its contacts to prevent the immediate picking up of said signal repeating relay, means for subsequently temporarily interrupting the circuit of said signal whereupon it will become deenergized to close the new circuit prepared for said repeating relay to pick it up and thereby hold the circuit of said signal open after said temporary means has ceased to function, and means for thereafter automatically releasing said slow to operate relay to again effect the release of said repeating relay and the consequent energization of said signal.
13. In a traffic control system for a stretch of track having a plurality of track switches associated therewith and which is divided up into a plurality of track relay equipped sections, a signal at the entrance to the stretch for governing traffic therethrough, a remotely controlled signal control relay for clearing said signal, an approach locking relay for preventing the operation of one of said switches after the signal has been cleared, route locking relays under control of said approach locking relay for preventing the remainder of said switches being operated after said signal has been cleared, a relay normally energized over a circuit including contacts of said signal control relay and released thereby when said signal control relay is operated to clear said signal, contacts on said normally energized relay opened by its release to thereby release said approach locking relay to effect the locking of all switches in the stretch, and a circuit for clearing said signal completed only after all of said switches have been locked and all track sections of the stretch are unoccupied as evidenced by the picked up condition of their associated track relays.
14. In combination, two sections of railway track, a signal at the junctions of said sections for governing traffic through one of them, a circuit for clearing said signal when closed, an approach locking relay having back contacts included in said circuit, a stick circuit for holding said relay energized, means operated to close one point in said first circuit and to open said stick circuit to enable said approach locking relay to complete the closure of said first circuit, said means being again operable to again open the

specified one point in said first circuit to immediately return said signal to stop, means responsive to the return of such signal to stop when said other section is unoccupied to immediately complete a pick-up circuit for said approach locking relay, means responsive to the occupancy of said other section when such signal returns to stop for completing a pick-up circuit for said approach locking relay a fixed interval of time after the return of said signal to stop, and another signal for governing traffic through said sections having a clearance circuit including front contacts of said approach locking relay.

15. In combination with a stretch of track divided into a plurality of insulated track sections each provided with a track relay and certain sections of which have railway track switches associated therewith, a semi-automatic non-stick signal for governing the movement of traffic into the stretch from one end, a semi-automatic stick signal for governing traffic entering the stretch from the other end, normally energized approach and route locking relays effective when deenergized to prevent movement of their associated switches, operator controlled means for releasing certain of said relays and for clearing one of said signals to enable a train to enter the stretch, and means rendered effective by the release of said operator controlled means to immediately energize the approach locking relay of the first switch equipped section of the stretch encountered irrespective of the location of the train in the stretch.

16. In a signaling system, a signal, a relay energized over a circuit including contacts of said signal closed when the signal is deenergized, contacts on said relay normally holding the circuit for energizing said signal open, a second relay having a pick-up circuit closed when the energizing circuit for said signal is closed, a third relay operable to release said first relay to complete circuits through said signal and said second relay respectively, the contacts on said signal opening a second point in the circuit of said first relay when the signal is energized and before said second relay has picked up, and contacts closed by said second relay effective to again pick up said first relay in case the opening of the contacts of said signal has failed to remove operating potential from the circuit of said first relay.

17. In combination, a stretch of railway track, a signal for directing traffic into the stretch, a repeating relay for said signal having a circuit including contacts of said signal, a signal control relay having contacts also included in said circuit and operated to effect the release of said relay, a circuit for clearing said signal including back contacts of said signal repeating relay and front contacts of said signal control relay respectively, another relay having a circuit closed by said signal control relay when picked up and having contacts closed around the contacts opened by the picking up of said signal control relay after the signal has had time to clear whereby the release of said signal repeating relay and the consequent clearance of said signal will be annulled in case there is stray operating current applied to said circuit at any point between the signal control relay contacts and the contacts of the signal itself.

18. In combination with a stretch of railway track provided with a railway switch, a signal for governing traffic entering the stretch, a signal repeating relay for said signal, an approach locking relay effective when deenergized to prevent

- movement of the associated switch and itself having a stick circuit including front contacts of said signal repeating relay, a signal control relay for clearing said signal having contacts included in a circuit for said signal repeating relay, a slow acting relay having an energizing circuit including contacts of said signal control relay, and a pick-up circuit for said approach locking relay including front contacts of said slow acting relay. 5
19. In combination with a stretch of railway track having a railway switch associated therewith, a normally deenergized signal, a signal repeating relay energized when said signal is in its normal position, an approach locking relay for said switch energized over a stick circuit including front contacts of said signal repeating relay, a signal control relay operable at will and having normally closed contacts included in the circuit of said signal repeating relay whereby operation of said signal control relay effects the release of said signal repeating relay, a slow acting relay, a circuit for energizing said slow acting relay including front contacts of said signal control relay; a circuit for energizing said signal closed jointly by said control, approach locking and repeating relays; and a pick-up circuit for said approach locking relay including front contacts of said slow acting and signal repeating relays respectively. 10
20. In combination with a stretch of railway track having a switch associated therewith, a signal for directing traffic into the stretch, a signal control relay operated to clear said signal and released to return said signal to stop, an approach locking relay for preventing movement of the switch after said signal has been cleared, a slow acting relay operated through the medium of said signal control relay when the latter relay is operated, a pick-up circuit for said approach locking relay including front contacts of said slow acting relay, and a stick circuit for said approach locking relay including contacts closed only when said signal is at stop. 15
21. In a signaling system, a signal, a normally energized signal repeating relay, a signal control relay operable at will and having normally closed contacts included in the circuit for said signal repeating relay whereby operation of said control relay effects the release of said signal repeating relay, a circuit for clearing said signal under the joint control of said signal control and repeating relays respectively, a slow acting relay having an energizing circuit closed by said signal control relay when said control relay is operated to clear said signal, means actuated by said signal when cleared to open a second point in the circuit for said repeating relay before said slow acting relay picks up, means for subsequently opening the circuit for said signal, and a new circuit for said repeating relay prepared by said slow acting relay and completed by said signal after the circuit for said signal is opened. 20
22. In combination, a section of railway track including a switch, a signal for governing traffic movements in a given direction over said switch, a first and a second approach section of said railway track over which traffic movements in said given direction approach said signal, an approach locking stick relay, an auxiliary stick relay, a pick-up circuit for said approach locking relay controlled by a front contact of said auxiliary relay and closed only if said first approach section is unoccupied, a second pick-up circuit for said approach locking relay which is normally open but which is at times closed independently of traffic 25
- conditions in either of said approach sections, a stick circuit for said approach locking relay closed if said signal is controlled to indicate stop, a pick-up circuit for said auxiliary stick relay controlled by a front contact of said approach locking relay, a stick circuit for said auxiliary stick relay closed only if said second approach section is unoccupied, and means controlled in part by said approach locking relay for controlling operations of said switch if said approach locking relay is energized. 30
23. In combination, a section of railway track including a switch, a signal for governing traffic movements in a given direction over said switch, an approach section of said railway track over which traffic movements in said given direction approach said signal, an approach locking stick relay, an auxiliary stick relay, a pick-up circuit for said approach locking relay controlled by a front contact of said auxiliary relay, a second pick-up circuit for said approach locking relay which is at times closed independently of traffic conditions in said approach section, a stick circuit for said approach locking relay closed if said signal is controlled to indicate stop, a pick-up circuit for said auxiliary stick relay controlled by a front contact of said approach locking relay, a stick circuit for said auxiliary stick relay closed only if said approach section is unoccupied, and means controlled in part by said approach locking relay for controlling operations of said switch if said approach locking relay is energized. 35
24. In combination, a stretch of railway track including a switch, a signal for governing traffic movements in a given direction over said switch, an approach locking stick relay, an auxiliary stick relay, a pick-up and a stick circuit for said auxiliary stick relay one of which is controlled by a front contact of said approach locking stick relay and the other of which is controlled by traffic conditions and is closed only if said stretch of track is unoccupied for a given distance in the rear of said signal, a pick-up and a stick circuit for said approach locking stick relay one of which is controlled by traffic conditions which are independent of traffic movements approaching said signal in said given direction and the other of which is closed only if said signal is controlled to indicate stop, a second pick-up circuit for said approach locking stick relay controlled by a front contact of said auxiliary stick relay whereby said second pick-up circuit will not be closed due to a loss of shunt of the track in the rear of said signal while a train is approaching within said given distance in the rear of said signal, and means controlled in part by said approach locking relay for controlling operations of said switch if said approach locking relay is energized. 40
25. In combination, a stretch of railway track, a signal for governing traffic movements over said stretch, a signal control relay, a signal repeating relay, an energizing circuit for said signal repeating relay controlled by said signal and by said signal control relay and closed only if said signal indicates stop and if said signal control relay is deenergized, a circuit for clearing said signal controlled by said signal control relay and by said signal repeating relay and energized only if said signal control relay is energized and said signal repeating relay is deenergized, an auxiliary relay controlled by said signal control relay in the energized condition and constructed to close its front contacts after said signal has left its stop condition, and a branch path closed by a front contact of said auxiliary relay around the 45

- 70
- 75

portion of the energizing circuit for said signal repeating relay which is controlled by said signal control relay.

26. In combination, a stretch of railway track, a signal for governing traffic movements over said stretch, a signal control relay, a signal repeating relay, an energizing circuit for said signal repeating relay including a contact closed by said signal when said signal indicates stop and also including a back contact of said signal control relay, a circuit for clearing said signal including a front contact of said signal control relay and a back contact of said signal repeating relay, a slow acting auxiliary relay, a circuit including a front contact of said signal control relay for energizing said auxiliary relay, and a branch path including a front contact of said auxiliary relay connected around the back contact of said signal control relay in the energizing circuit for said signal repeating relay.

27. In combination, a stretch of railway track containing a switch, a signal for governing traffic

movements over said switch, a manually controllable device, and means controlled by said device for clearing said signal only under clear track conditions in said stretch if said switch occupies a given position and for clearing said signal independently of said track conditions in said stretch if said switch occupies a second given position.

28. In combination, a stretch of railway track containing a switch, a track circuit for said stretch including a track relay, a signal for governing traffic movements over said switch, a manually controllable device, and means controlled by said manually controllable device and by said switch and said track relay for clearing said signal when said switch occupies a given position only if said track relay is energized and for clearing said signal when said switch occupies a different position independently of the condition of said track relay.
